FIREARM CONTAINER

Stanley W. Fish, Springfield, Mass., assignor to
the United States of America as represented
by the Secretary of War

Application May 6, 1948, Serial No. 25,441

5 Claims. (Cl. 206—3)

(Granted under the act of March 3, 1883, as
amended April 30, 1928; 370 O. G. 757.)

1

This invention relates to a sealed container for storing firearms over a protracted period of time.

The invention described in the foregoing specification, if patented, may be manufactured and used by or for the Government for governmental purposes without the payment to me of any royalty thereon.

The storage of firearms, particularly military firearms for any long protracted period has heretofore been a serious problem for the reason that no definite assurance could be had that the firearms would stay in first-class condition during this period without considerable attention. The main contributing factor causing concern in the storage of firearms is corrosion due to excessive moisture in the air. As firearms are fabricated largely of steel, such metal is of course subject to deterioration due to the corrosive elements of the atmosphere unless properly protected.

In the past the procedure has been to heavily coat the firearms with grease and then enclose the firearm in a wooden container whereupon the container was placed in storage. There are however, numerous drawbacks to such a procedure among them being the difficulty in cleaning the firearm upon removal from the wooden container. The heavy coating of grease had to be removed by the use of a suitable solvent which involved complete disassembly of the firearm. Obviously this necessitated a great deal of valuable time-consuming labor. It is apparent therefore that such firearm could not be used immediately upon withdrawal from the container in time of emergency. In addition, the heavy coating of grease did not insure full protection against the corrosive elements of the atmosphere because such coating may not have been properly applied. Furthermore, the wooden container holding the firearm was not of sufficient strength to positively insure that such container would not be broken if dropped and still further, the wooden container would not exclude moisture.

Accordingly it is an object of this invention to provide a sealed container for storing firearms for a long period of years under any climatic condition.

Another object of this invention is to provide a container for firearms which will withstand extremely rough handling without damage to the firearms contained therein.

The specific nature of the invention as well as other objects and advantages thereof will clearly appear from a description of a preferred embodiment.

ment as shown in the accompanying drawings in which:

Fig. 1 is a side view of the firearm container shown partly broken away to illustrate the manner of mounting the firearms therein.

Fig. 2 is a side view of the firearm holder.

Fig. 3 is a sectional view taken along the line 3—3 showing the spider utilized to separate the firearms.

10 Fig. 4 is a side view taken along the line 4—4 showing one of the end plates provided with the various indentations thereon for receiving the end parts of the firearms.

In Fig. 1 there is shown in assembled relation a 15 firearm container constructed in accordance with the teachings of this invention. Such container comprises essentially a drum 10, a firearm holder 11 contained within drum 10 and disks 12 and 13 for closing and sealing each end of drum 10.

20 Drum 10 is of conventional construction and is preferably fabricated of sheet steel for optimum strength. To increase the rigidity of such drum a plurality of annular stiffening ribs 14 are provided about the periphery thereof. The bottom 25 of drum 10 is closed by inserting sealing disk 12 therein and seam welding disk 12 to drum 10 as shown at 15. Firearm holder 11 comprises a tube 16, a pair of spaced spiders 17 and 18 welded to tube 16 and end plates 19 and 20 welded to opposite ends of tube 16. Spiders 17 and 18 are formed 30 of pressed steel and are provided with a plurality of substantially U-shaped firearm receiving openings 21 and 22 near the outer periphery of such spiders. Openings 21 in spiders 17 and 18 receive 35 a portion of the butt stock of a firearm 23 to be stored in the container while openings 22 receive a portion of the forward end of firearm 23. Openings 21 and 22 are preferably evenly spaced about spiders 17 and 18.

40 End plates 19 and 20 are disk-like members and each are provided with a plurality of circular indentations or sockets 24 radially disposed and evenly spaced to receive the muzzle end of firearms 23. A plurality of knob-like projections 35

45 are also provided on end plates 19 and 20 disposed as shown in Fig. 4 for a purpose to be presently described. End plates 19 and 20 are spaced apart at the end of tube 16 at a distance to just permit assembly of a firearm into spiders 17 and 18 so

50 that while the muzzle end is resting in socket 24, the butt end will be resting on the opposite plate with the butt on top of knob 35. With the firearms so stacked the center of thrust on the butt of the firearm is then on a direct line with the axis of the firearm thereby substantially elimi-

nating any breakage of stocks. The firearms 23 are placed in firearm holder 11 in such fashion that the adjacent firearms will have their ends reversed as shown in Fig. 1. By so stacking the firearms it is obvious that a greater number can be accommodated by drum 10. A pad 25 of non-organic material separates the muzzle from the bottom of socket 24 to prevent any damage thereto and to provide a more resilient mounting of the firearm. Pad 25 is preferably made of fibre glass matted with silicone.

When firearms 23 are placed within holder 11, a steel band is placed in surrounding relationship with the firearms at a point opposite the pistol grip of the firearm as shown at 26. A pad of 15 non-organic material 27 is placed under each band 26 in order to protect the firearms from damage caused by tightening such band. A keeper 28 of well known construction is utilized to secure band 26 tightly about the firearms 23. Thus when 20 bands 26 are tightened about the firearms, such firearms are tightly secured within openings 21 and 22 of spiders 17 and 18.

The firearm holder 11 is then inserted in drum 10. To prevent axial displacement of such holder a circular rib 29 is provided on the inside of each of the sealing disks 12 and 13. An outwardly extending peripheral flange 30 provided on each end plate 19 and 20 engages the rib 29 thereby preventing axial displacement of holder 11.

The stocks of each firearm 23 are initially subjected to a heating process to reduce the moisture content thereof to not over 5% by weight before placing in drum 10. Each firearm 23 is then lightly oiled so that each firearm may be put into action immediately upon withdrawal from the container. In order to control the moisture content contained in the air inside of drum 10 when disk 13 is finally sealed in place, a quantity of silica gel is enclosed along with holder 11. The amount of silica gel enclosed is adjusted to keep the moisture in air contained in drum 10 within a relative humidity of not over 30%. The drum is then ready for sealing. Sealing disk 13 is then seam welded at 31 to exclude the elements from the interior of drum 10.

The exterior of drum 10 is then protected by galvanizing and painting or by providing some other rust-resistant coating thereon and then painting over such coating. No treatment of the inside of drum 10 is necessary because of the controlled atmosphere therein which substantially eliminates corrosion.

From the foregoing description it is clearly apparent that there is here provided a container for firearms which seals the firearms against the corrosive elements of the atmosphere and which will protect firearms contained therein for years without damage from corrosion or other harm. The drum utilized in this invention is of sufficient strength to withstand more than the normal abuse incurred in handling such containers while at the same time supporting the firearms in holder 11 in such fashion that the firearms will not be disturbed or injured in any way.

Another decided advantage of storing firearms in the manner of the teachings of this invention is that such container may be conveniently handled and if necessary may even be floated to shore from a ship. The firearms contained therein may be readily removed by cutting just below the seam welded portion of either sealing

disk 12 or 13 and simply sliding out firearm holder 11. Bands 26 are then readily severed whereupon the firearms may be removed from spiders 17 and 18 and the gun rapidly put into use because of the very light oiling of the barrel and working parts.

I claim:

1. A waterproof container for firearms comprising a tube, a disk member adapted to be inserted in each end of said tube and sealed in place, a holder in said container comprising a support member having a pair of spaced spiders secured thereto, said spiders being adapted to receive a plurality of firearms, a flanged end member secured at each end of said supporting member for longitudinal support of the firearms, and means on each of said disk members engageable by said flanged end members for securing said holder against axial displacement.

2. A firearm storage container comprising a tube, a flanged end member adapted to be inserted in each end of said tube and sealed in place, a holder adapted for insertion in said tube consisting of a central post having a pair of spaced spiders fixed thereon, said spiders having peripheral openings adapted to receive a plurality of firearms, means for securing the firearms to said spiders, a flanged disk secured to each end of said post, said disks having muzzle receiving sockets therein whereby said firearms are held out of contact with said tube, and means on each of said disk members engageable by said flanged end members for securing said holder against axial displacement.

3. The combination defined in claim 2 wherein said last mentioned means comprises a circular rib on said flanged end member.

4. A firearm storage container comprising a tube, a flanged end member adapted to be inserted in each end of said tube and sealed in place, a holder adapted for insertion in said tube consisting of a central post having a pair of spaced spiders fixed thereon, said spiders having peripheral openings adapted to receive a plurality of firearms, means for securing the firearms to said spiders, a pair of flanged disks, each of said disks having a plurality of muzzle receiving sockets radially disposed in the form of an inner ring and a plurality of butt stops radially disposed in the form of an outer ring in staggering relation with said muzzle receiving sockets, said disks being secured to each end of said post whereby each of said muzzle receiving sockets of one of said disks lie in the same plane as said butt stops of the other of said disks to receive a firearm therebetween with each adjacent firearm end being reversed to facilitate storing, and means on each of said disks engageable by said flanged end members for securing said holder against axial displacement.

5. The combination defined in claim 4 wherein said last mentioned means comprises a circular rib on said flanged end members.

STANLEY W. FISH.
